UNITED STATES PATENT OFFICE.

CORNELIA J. CHADWICK, OF NEWPORT, RHODE ISLAND.

CARRIER.

1,096,489.

Specification of Letters Patent.

Patented May 12, 1914.

Application filed July 11, 1913. Serial No. 778,528.

To all whom it may concern:

Be it known that I, CORNELIA J. CHADWICK, a citizen of the United States, residing at Newport, in the county of Newport and State of Rhode Island, have invented a certain new and useful Carrier, of which the following is a specification.

My present invention relates to improvements in carriers of the type for which were granted to me Letters Patent of the United States No. 620,694, dated March 7, 1899; these being essentially flexible carriers adapted to the transportation of wounded, or otherwise disabled, persons by their attendants, as from battle fields or decks of vessels in action, the said carriers being characterized by their compactness, and stowability, when not expanded for use, and by their comparative non-interference with freedom of movement on the part of the bearers when loaded.

The objects of my present invention comprise impartation of greater security and comfort to the patient during transportation in such carriers, simplification and acceleration of transformation from the folded to the set-up, and connected, condition, and adaptation of such carriers not only to patients capable of sitting postures, but also to those completely prostrated. I attain these and other useful objects by means of the devices, and combinations of devices, illustrated in the accompanying drawings in which:—

Figure 1 is a plan view of a carrier unit comprising my improvements and unfolded into substantially a single plane. Fig. 2 is a similar view showing two of said units combined with each other, and with poles, to constitute a stretcher, the major marginal projections of one of said units being raised out of said plane and clutched together in position to secure the patient. Fig. 3 is a vertical section taken on the line 3—3 of Fig. 2, seen in the direction of the arrow. Fig. 4 is a perspective view of a bearers'-harness adapted for combination with the unit of Fig. 1. Figs. 5 and 6 are perspective views illustrating the adjustment to the bearer of the harness of Fig. 3, and seen respectively from the front and rear of the bearer. Fig. 7 is a perspective front view showing one method of combining the unit of Fig. 1 with the harnesses of Fig. 4 when worn by the bearers. Fig. 8 is the same as Fig. 7 with addition of the patient seated in the carrier. Fig. 9 is a perspective view illustrating the

reverse coupling of the unit of Fig. 1 to the harnesses whereby the arms of the bearers are left comparatively free. 60

Similar letters refer to similar parts throughout the several figures.

a represents the body supporting piece of one of my improved carrier units. It is made of any sufficiently strong, flexible, material, as, for instance, canvas. It is, when expanded flat, rectangular and somewhat oblong as shown. It comprises disposed in parallelism with each other and with its central longitudinal axis, on opposite sides thereof, thereto annexed tubular receptacles *C*, *C'*, for insertion of bearing-poles *c*, *c'*, preferably consisting, as indicated in the drawings, of a unitary hem of the constituting material having its edge secured thereto 75 as by the seam *b'* (see Fig. 3) thus constituting said tubular receptacle for a pole, the entire length of two opposite sides of the body supporting piece *a*, but it will be understood that other equivalently operating 80 devices might be employed as for example a row of alined rings secured to said body member along each of opposite sides thereof. My carrier unit also comprises adjacent one side of its said body supporting piece *a*, a pair of 85 therewith connected therefrom outwardly and oppositely presented like suspenders *a*², *a*², disposed to extend from said body-supporting piece in opposite directions in parallelism with said side and each carrying secured thereto adjacent its outward extremity a clutching device *a*³, which is preferably any usual form of clutching device, for example such as the well known "harness spring snap", though buckles or other fastening device might less conveniently be employed. The suspenders *a*², *a*², are made 90 of flexible material for example canvas the same as the body-member *a*, and are secured thereto in any convenient manner, as 100 for example by rivets *m*, or by stitching, and said suspenders *a*², *a*², are preferably made of a single unitary strip of material extending completely across one end of said body supporting piece as indicated in Figs. 1 and 105 3. My carrier unit also comprises secured thereto in any convenient manner, adjacent that end of said body-member *a* which is opposite to that carrying the projections *a*², *a*², a pair of outwardly and oppositely presented suspenders *e*, *e'*, which are shorter 110 than the suspenders *a*², *a*², and are similarly provided with clutches similar to those hereinbefore described. It will be observed how-

ever, and this is of essential importance, that the clutches of the shorter suspenders e , e' , are, when the carrier unit is spread out flat as shown in Fig. 1, located much nearer the 5 center of said supporting piece a than are the clutches of the longer suspenders a^2 , a^2' . My carrier unit also comprises secured thereto in any convenient manner, intermediate its said clutches e , e' , a therefrom outwardly 10 presented fifth clutch e^3 , similar in construction to the clutches heretofore described.

A form and construction of bearer-harness adapted for use in combination with my said unit carrier comprises, as shown, a 15 relatively-broad shoulder pad f from which hang the carrying-straps g , g' , each bearing at its nether extremity a ring i or k , (Fig. 4) adapted to be engaged respectively by one of the clutches e , e' , or a^3 , a^3' . A waist belt 20 h is combined with the straps g , g' , in any convenient manner so as to aid in keeping them in desired position.

It follows from the above described constructions that my carrier-unit is attachable, 25 and detachable, from the harnesses on the bearers with the greatest possible simplicity and rapidity. But what is more important, the relation and proportions of the parts are such that when so attached there is provided not only a comfortable flexible support for the patient's seat when in sitting posture as shown in Fig. 8, but also, unitary with said seat support, an upward extension thereof constituting a further support 30 against which the patient's back may securely rest while in said posture. On the other hand, support is also afforded to the under parts of the thighs up to the knees. The entire body of the patient is thus securely held in the carrier unit against displacement in either a forward or backward direction while being carried, and transverse displacement is sufficiently guarded against 35 by the presence of the bearers' bodies which contact with the patient's on either side.

The usual method of combining the harnesses with the carrier unit is shown in Figs. 7 and 8. In this the patient faces in the same direction as the bearers, and therefore 40 the latter are further enabled to support his head with their hands or arms as shown in Fig. 8. But if the patient be sufficiently strong and it is desirable that the bearers' arms be free to handle weapons, or to assist 45 in climbing up or down, the direction of attachment of the carrier unit to the harnesses may be reversed as shown in Fig. 9, this bringing the patient back to back with the bearers and leaving their hands and arms 50 free for any purpose.

It is designed that pluralities of my carrier units shall be at all times available, as for instance in field or other hospitals, with

relief corps, or on board ship, etc. Whenever, therefore, the condition of the patient 65 is such as to preclude his transportation in sitting posture, the construction of such units is such as to enable a pair of them to immediately provide means for constructing a litter suitable for conveyance of the patient recumbently. To this end the carrier units are combined with each other by interlocking together the clutches e , e' , and e^3 , of the one with the corresponding clutches of the other as shown in Fig. 2 after which 70 the poles c , c' , being thrust through the tubular receptacles C , C' , a litter is thereby constituted and the suspenders a^2 , a^2' , of the respective units being drawn up and their clutches a^3 , a^3' , inter-clasped as shown in Fig. 75 3, the body of the patient within them is thereby hindered from falling off.

What I claim as new and desire to secure by Letters Patent is the following, viz:—

1. The combination, in a carrier, of a 85 pair of bearers'-harnesses; a flexible, rectangular, body-supporting piece; a pair of flexible suspenders each connecting a corner of one side of said body-supporting piece with one of said harnesses; and another pair 90 of longer suspenders each connecting a corner of the opposite side of said body-supporting piece with one of said harnesses, whereby said body piece is enabled to simultaneously support, as against fore and aft 95 displacements, the back, the seat, and the under part of the thighs of the patient thereby carried.

2. The combination, in a carrier, of a 100 flexible body-supporting piece having tubular receptacles disposed in parallelism with each other adjacent to two opposite sides thereof; adjacent an edge of said piece intermediate said receptacles a pair of flexible 105 suspenders disposed to extend in opposite directions in parallelism with said edge; and, adjacent to the opposite edge of said piece, a pair of shorter suspenders substantially as and for the purposes specified.

3. The combination, in a carrier, of a 110 flexible body-supporting piece having tubular receptacles disposed in parallelism with each other adjacent to two opposite sides thereof; adjacent an edge of said piece intermediate said receptacles a pair of flexible 115 suspenders disposed to extend in opposite directions in parallelism with said edge; adjacent to the opposite edge of said piece, a pair of shorter suspenders, and a fastening 120 device disposed between said last mentioned suspenders substantially as and for the purposes specified.
